THERMAL INSULATOR

John Campbell and Robert G. Quinn, Glens Falls,
N. Y., assignors to International Paper Company,
New York, N. Y., a corporation of New
York

Application February 24, 1933, Serial No. 658,371

3 Claims. (Cl. 154—45)

This invention relates to an insulation construction and particularly to that class of insulation construction which includes units built up of a plurality of sheets secured together in any desired manner.

Built-up thermal insulators of the character just indicated, as heretofore made, have either lacked mechanical strength or do not provide a satisfactory insulating medium particularly adapted for refrigerator or building constructions. In many thermal insulator constructions the insulating value has been sacrificed to obtain the desired mechanical strength.

The sheets making up the units must be reinforced or otherwise strengthened, and are consequently not only costly to manufacture but often do not possess the necessary and desired insulating characteristics. The primary feature of this invention, therefore, is to provide a new and improved insulation unit which effectively meets all of the requirements of a satisfactory insulator and yet, which at the same time, is relatively cheap to manufacture and assemble.

Another feature of this invention is to provide a new and improved thermal insulation unit made up of a plurality of sheets of paper which have been previously impregnated, coated, contained or saturated with a waterproofing material and then corrugated. Sheets thus formed may be assembled into a pack and then sewed or stapled together, thus avoiding the use of adhesive to hold the sheets together.

A further feature of this invention is to provide an improved thermal insulation unit comprising a plurality of sheets of waterproofed corrugated paper united together in such a manner that the number of contacts between sheets through a cross section of the unit and the area of such contact points are reduced to a minimum, thereby reducing the rate of flow of heat through the unit.

A still further feature of this invention is to provide an insulation construction made up of a plurality of corrugated sheets of paper which have been previously treated with a waterproofing and/or stiffening material of such character that the air cells formed by the corrugations may be designed within close limits to obtain a minimum heat transfer by convection. In other words, the optimum still air condition may be obtained. Moreover, the material which the sheets contain, through impregnation, coating or through addition in manufacture previous to formation into sheets, renders the sheets resistant to capillary and hygroscopic action. Sheets so

treated do not have their strength and insulating value appreciably decreased when exposed to moisture.

With these and further features in view as will in part be hereinafter stated and in part become more apparent, the invention comprises certain novel constructions and arrangement of parts as subsequently specified and claimed.

In the accompanying drawing,—

Fig. 1 is a perspective view of the new and improved insulation unit; parts thereof being broken away to show certain details of construction.

Fig. 2 is an end elevation of a portion of the unit looking in the direction of the arrows 2—2 of Fig. 1.

Fig. 3 is a similar view but showing a modified form of insulation unit.

Referring now more particularly to the drawing in which like numerals indicate like parts there is shown an insulation unit 10 comprising a plurality of superimposed corrugated sheets 11. Each of these sheets 11 consists of a length of paper which has been saturated or impregnated with asphalt up to the extent of 50% of its weight. The paper used in constructing the improved insulating unit is preferably made by using a well-beaten fibre, silicate of soda, and by saturating afterward with steam-blown asphalt or other hard waterproofing substance which has the characteristic of forming a rigid film. It will be appreciated that the stiffer the sheet is, the lower the weight of sheet necessary, and consequently the better the resultant insulation, since the solid fraction of the product is less. I have found that the minimum requirements are that the sheet must be stiff enough so that, when corrugated, the corrugations will retain their shape and not flatten out. The impregnation or coating agent must be sufficiently thermo-plastic to avoid excessive brittleness during corrugating.

The use of too brittle an impregnating agent might readily cause the sheet to break or to peel off in passing through the corrugating rolls. Hence, if the higher melting bitumens are used the paper need only be impregnated to the extent of 25% or less of its weight. If desired, however, the paper may be saturated or impregnated with Montan wax, sulphur, coumar resin or other synthetic resins, or gums. Paper thus treated is comparatively rigid and can be corrugated with less corrugations per running foot than has heretofore been considered possible. In the corrugating of paper which has not been treated in this manner it has been found necessary to glue

or cement a facing sheet to the corrugated paper to enable such paper satisfactorily to serve the purpose for which it was intended. The use of asphalt impregnated paper does away with the handling and equipment involved in pasting the facing sheet on the corrugated paper.

As will be noted the flutes 12 of alternate sheets of asphalt impregnated paper are disposed at right angles to the flutes 13 of adjacent sheets. 10 The unit is held together by stitching 14. This construction not only affords considerable stiffness in the finished unit but also serves to reduce the flow of heat therethrough. In prior practice the paper usually employed would not possess sufficient mechanical strength unless the paper was so corrugated that the flutes thereof were of considerable height and the number of flutes in each running foot of paper was accordingly great. When a number of such sheets, having 15 cemented or glued thereto facing sheets, were built into a unit the number of positive contact points through a cross section of the unit and the area of such contact points were large. The insulating value of the completed unit was low 20 and the cost of manufacture high.

By the use of corrugated asphalt impregnated or saturated sheets the above described difficulties were avoided. The sheets thus formed can be stitched together avoiding the formation of 30 positive contacts between sheets, the number of places of contacts can be reduced as can also the area of such contacts. Such construction consequently reduces the flow of heat through the unit to a minimum and is a distinct advance in the manufacture of suitable insulation units. Since 35 paper impregnated or saturated with asphalt is moisture resistant the unit may be subjected to moisture containing fluids without the danger of decay and without an appreciable decrease in the insulating value thereof.

In many cases it is necessary that the thermal insulating unit be so treated as to withstand the effect of fungi and insects. Thermal insulating units possessing this characteristic may be readily obtained by treating the paper with copper 45 salts, arsenic compounds, chlorinated diphenyls or naphthalenes.

In Fig. 3 there is shown a modified form of insulation unit 10' in which the flutes 15 are themselves provided with flutes 16. Such construction serves to still further decrease the area of the contact points between the sheets making up the unit.

In assembling the unit a plurality of webs of 50 corrugated asphalt impregnated paper are fed at

right angles to the frictional rolls of a conventional stitcher with enough space between them to permit the insertion of sheets of similarly treated paper equal in length to the width of the several webs. The corrugations of the paper 5 moving in the continuous webs are parallel with the friction rolls of the stitcher. The corrugations of the sheets run at right angles to the friction rolls of the stitcher. When these latter sheets have been moved into superimposed relation with the webs of material they are cut, and the insulation thus formed is sewed together without compressing the layers forming the said unit. It may be sometimes desirable to use sheets 10 varying in width. After stitching the assembled 15 web is slit into the desired dimensions.

From the above description it will be appreciated that the invention comprises a new and novel thermal insulation unit which satisfactorily meets all requirements of an insulator designed 20 primarily for use in refrigerator and building construction. It will also be readily appreciated by those skilled in the art to which this invention appertains that several modifications may be be made in the construction and arrangement of 25 parts without departing from the spirit of the invention or the scope of the appended claims.

We claim:

1. A thermal insulator comprising a plurality of superposed sheets of waterproofed corrugated 30 paper, each flute of which is itself corrugated throughout its length whereby to reduce the effective area of contact between the corrugations of the sheets, and stitching connecting said sheets together.

2. A thermal insulator comprising a plurality of superposed sheets of waterproofed corrugated paper, the flutes of alternate sheets running at an angle to flutes of adjacent sheets, each flute of each sheet being in itself corrugated throughout its length, whereby to reduce the effective 40 area of contact between the corrugations in the sheets, and stitching connecting said sheets together.

3. A thermal insulator comprising a plurality 45 of sheets of corrugated paper arranged in superimposed relation, each sheet being saturated up to 50% of its weight with asphalt capable of forming a rigid film whereby the corrugations of each sheet will retain their shape, the flutes of 50 adjacent sheets having substantially point contact with each other, and means connecting said sheets together.
